(57) **CLAIM**

The ornamental design for an oven range as shown and described.

DESCRIPTION

1. Oven range
1.1: Front, top perspective
1.2: Front, bottom perspective
1.3: Front
1.4: Back
1.5: Left
1.6: Top
1.7: Bottom
1.8: Enlarged
1.9: Enlarged
1.10: Reference
1.11: Enlarged reference
The omitted right view is a mirror image of the left view; reproductions 1.8 and 1.9 are enlarged views of the encircled portions in reproduction 1.1 respectively; reproduction 1.10 shows a state of use in which the hidden door handles are pulled out; reproduction 1.11 is an enlarged view of the encircled portion in reproduction 1.10; the broken lines shown in the reproductions depict portions of the oven range and form no part of the claimed design.

1 Claim, 11 Drawing Sheets
